Indiana

Filed Apr. 21, 1966, Ser. No. 1,968

Term of patent 14 years

(Cl. D81—25)

Fig. 1.

Fig. 2.

Fig. 3.

FIG. 1 is a front perspective view of a cooking surface and ventilator combination embodying my new design with the ventilation tower in a raised operating position.

FIG. 2 is a view similar to FIG. 1 with the ventilation tower in a closed position.

FIG. 3 is a front perspective view of a further modified form thereof.

The dominant features of my design reside in the portions shown in full lines. The right side is substantially the same as the left side shown.

I claim:

The ornamental design for a cooking surface and ventilator combination, as shown and described.
